US00D606971S

(12) **United States Design Patent**
Christopher et al.

(10) **Patent No.:** **US D606,971 S**
(45) **Date of Patent:** **** Dec. 29, 2009**

(54) **AUDIO DEVICE**

(75) Inventors: **Stephen M. Christopher**, Chicago, IL (US); **Michiel S. Knoppert**, Chicago, IL (US)

(73) Assignee: **Motorola, Inc.**, Schaumburg, IL (US)

(**) Term: **14 Years**

(21) Appl. No.: **29/330,126**

(22) Filed: **Dec. 30, 2008**

(51) **LOC (9) Cl.** **14-01**

(52) **U.S. Cl.** **D14/205**

(58) **Field of Classification Search** **D14/205, D14/206, 223, 142, 188, 192; 181/129, 130, 181/137; 379/430, 433.01; 381/381, 370, 381/330, 322, 324, 328; 128/864, 866; 455/575.1, 455/575.2; D24/174**

See application file for complete search history.

(57) **CLAIM**

The ornamental design for a audio device, as shown and described.

DESCRIPTION

FIG. 1 is a perspective view of an ornamental design for a audio device;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken line in FIGS. 1–7 showing environmental structures is for illustrative purposes and forms no part of the claim design.
